MECHANICAL STOKER

Fred H. Ream, Montgomery County, near Dayton, Ohio

Application October 2, 1936, Serial No. 103,634

3 Claims. (Cl. 83—52)

This invention relates to new and useful improvements in mechanical stokers, and more particularly to the type of stoker illustrated and described in my application for United States Letters Patent, Serial No. 76,651, filed April 27th, 1936, distinguishing from the latter in that in the present case the bottom is mounted for a swinging movement about the feed screw.

It is one of the principal objects of this invention to provide a swinging bottom below the usual feed worm shaft in mechanical stokers, to keep the material in constant agitation throughout the hopper.

Frequently in automatic coal stokers of the underfeed type, in using fine, damp or dirty coal, or coal having roots, leaves or other foreign matter intermixed therein, such material packs in the throat of the hopper, thereby bridging over, and shutting off the supply of such material, to the feed screw. The result is a diminished or suspended supply of such material to the retort, with attendant discomfort and annoyance.

Similar interruptions necessarily ensue in the normal delivery of material to the retort by the feed screw in the case of lump coal, when lumps which are too large to pass through the feed tube become numerous around the feed screw, thereby bridging over the latter and restraining any finer material which might lie above the lumps from reaching the feed screw.

My swinging bottom constantly maintains a seam or cleavage in the material in a vertical plane extending longitudinally with the axis of the feed screw, and directly above the same, whereby such material, embodying loose particles, will gravitate without hindrance directly into the path of the feed screw.

It is a further object of my invention to provide means whereby my swinging bottom may be actuated by the feed screw shaft.

Another object of my invention is the provision of a swinging bottom which may be made as a single integral casting including the lower half of the crusher cone, with the upper half of the cone detachably connected thereto for removal to permit the withdrawal of obstructions, and the making of repairs. This bottom is mounted concentric with the feed screw and feed tube, being hung either on the feed screw shaft at the driving end or on the bearing in the hopper frame in such a manner that the feed shaft will run concentric therewith.

It is another object of my invention to adapt my swinging bottom to a coal bin, where it will impart the same cleavage in the material directly

above the feed screw to cause it to fall directly into the path of the same.

Other important and incidental objects will be brought out in the following specification and particularly set forth in the subjoined claims.

In the accompanying drawings, Figure 1 is a top view of a mechanical stoker with the lid open to reveal the swinging bottom. Figure 2 is a longitudinal, sectional view taken through the same. Figure 3 is a cross sectional view taken through the hopper on the line 3—3 of Figure 2. Figure 4 is a cross sectional view taken through the cone portion of the swinging bottom. Figure 5 is a top plan view of the swinging bottom, with the crusher cone top in place upon its base portion. Figure 6 is a side elevational view thereof. Figure 7 is a top plan view of the coal bin adapted to receive my swinging bottom. Figure 8 is a cross sectional view taken through the coal bin on the line 8—8 of Figure 7. And Figure 9 is a detail side view of one form of mechanism for actuating the swinging bottom.

In the accompanying drawings illustrating various forms of embodiment of my invention, the numeral 1 designates the hopper of an automatic, underfed stoker. Passing through the lower portion of the hopper 1, which will be hereinafter designated the outer hopper, is a feed screw shaft 2 to which is secured a conventional fuel feed screw 3.

Swingingly mounted upon the feed screw shaft 2, near its driven end within the outer hopper 1, is a bottom 4 which has an end boss portion 5 formed with an axial hole through which the shaft 2 projects and upon which the boss is free to turn. A gasket 5a surrounds the feed shaft 2 between its screw portion and the inner hopper to be hereinafter described.

The swinging bottom 4 preferably comprises a single, integral casting which includes an integral cone crusher extension 6 that has a flanged upper part 7 to receive a flanged top or cover section 8 which is adapted to be detachably bolted to it. (See Figures 1, 4, 5 and 6.) This upper half section 8 of the cone crusher part of the swinging bottom may be easily detached from the lower half 6 to permit the ready removal of obstructions, and the making of repairs.

At its feed tube end, the cone crusher part of the swinging bottom is formed with a spherical, annular surface 9 which rests against the spherical annular bearing surface 10 on the inside of a housing casting 11 to hold it concentric with the feed tube 12. To the end of this feed tube nearest the hopper there is demountably

secured by screws 13 the reduced end 14 of the housing 11 that surrounds the crusher cone end of the swinging bottom.

The housing 11 is provided at its rear end with 5 a flange 15 which is detachably bolted to the outer hopper 1, whereby when the bolts are removed, the housing may be slid back over the feed tube to expose the upper half of the cone crusher, to permit its removal.

10 Ribs, in this instance integral fins 16 of spiral form, are provided on the inner surface of the crusher cone sections of the swinging bottom. These fins project from the mouth of the cone to a point near its discharge end for cooperation 15 with the feed screw 3 in dividing into smaller pieces and moving through the cone, lumps of coal or other coarse material.

Formed on each side of the swinging bottom 4 is a projecting shaft or ledge 17 that is provided 20 with a recess to receive the lower end 18 of a half section 19 of an inner hopper 20. Curved clamps 21 secured to the bottoms of the inner hopper sections 19, 19 by bolts 22, engage the rounded outer surfaces of the projecting ledges 17, 17 on 25 the swinging bottom 4 to assist in hingedly securing the inner hopper sections thereto. (See Figure 9.)

For the purpose of swinging the bottom 4 of the inner hopper 20 simultaneously with the feed screw shaft 2, I have provided the following 30 means, although any other suitable means may be employed for this purpose if desired. Referring to Figure 9, the screw shaft 2 carries an eccentric 23 from which there projects outwardly 35 a rod 24 pivotally connected to the middle portion of a lever arm 25 adapted to be secured at one end to a fixed pivot (not shown). Pivotally secured to the other end of the lever arm 25 is a link 26 that is pivotally connected to the outer 40 end of an arm 27 secured to the swinging bottom 4, whereby when the screw shaft 2 is rotated, it will be swung to give a vertical, reciprocable movement to each half section 19 of the inner hopper 20 through an arc defined by the movement of its respective ledge 17.

45 In addition to its vertical movement, each hopper section 19 receives a horizontal reciprocating movement by virtue of the arc traversed by its respective ledge, so that when one section is raised and drawn in toward the center, the other section is lowered and thrown out. This movement of the inner hopper sections causes one half of the material carried by the hopper to be raised and distorted while the other half descends, effecting a cleavage of material directly above the feed screw 3.

In Figures 7 and 8 I have shown my swinging bottom incorporated in a coal bin 28 from which 50 coal is delivered to a furnace 29 by the feed screw 3 which passes through the cone crusher end of that bottom and the feed tube 12. Below the rigid open bottom 30 of the coal bin are inner hopper sides 31, 31 which are hingedly secured

5 to the ledge ends 17 of the swinging bottom 4. The latter is preferably swung about the feed shaft 2 by the eccentric means hereinbefore described and shown in dotted lines in Figure 7.

The feed shaft 2 is rotated by a gear 32 secured to its outer end and in mesh with a pinion 33 carried by a shaft 34 driven by a gear (not shown) in a gear box 35.

When employed in a coal bin, my swinging bottom will constantly maintain a seam or cleavage 10 in the coal in a vertical plane extending longitudinally with, and directly above, the axis of the feed screw 3 on the shaft 2.

I do not wish to be limited to the details of construction and arrangement herein shown and described, and any changes or alterations may be made therein within the scope of the subjoined claims.

Furthermore, while my invention is more particularly designed for use in connection with an 20 automatic stoker, it is equally applicable to the feeding of any material from a bin or hopper.

Having described my invention, I claim:

1. A mechanical stoker comprising a hopper, a feed screw shaft within said hopper, means for 25 rotating the feed screw shaft, a bottom pivotally mounted in said hopper for a swinging movement about the feed screw shaft, an eccentric carried by said shaft, a lever arm pivotally secured at one end to said hopper, a rod pivotally connecting 30 the eccentric and lever arm, and a link pivotally connected between said arm and the bottom to swing the same when the feed screw shaft is rotated.

2. In a mechanical stoker, a hopper, a feed 35 tube, a feed screw for forcing material from said hopper to the feed tube, a bottom pivotally mounted in said hopper for a swinging movement about the feed screw, means to rotate the feed screw and rock the bottom, a sectional 40 crusher cone whose lower half is cast integral with said bottom, and a housing detachably connected between the feed tube and the hopper and having a bearing seat for the feed tube end of said cone, the top section of said cone being removable for the withdrawal of obstructions 45 around the feed screw and the making of repairs.

3. In a mechanical stoker, a hopper, a feed 50 tube, a feed screw for forcing material from said hopper to the feed tube, a bottom pivotally mounted in said hopper for a swinging movement about the feed screw, means to rotate the feed screw and rock the bottom, a sectional crusher cone extension whose lower half is integral with 55 said bottom, a housing detachably connected between the feed tube and the hopper and having a bearing seat for the feed tube end of said cone extension, and fins on the interior of said cone extension, one section of said cone extension being removable for access to the feed screw and 60 fins to remove obstructions therefrom.

FRED H. REAM.
